UNITED STATES PATENT OFFICE.

SANDOR J. SOLTESZ, OF NEW YORK, N. Y.

ARMOR PROTECTOR FOR PNEUMATIC TIRES.

Application filed January 2, 1923. Serial No. 610,178.

To all whom it may concern:

Be it known that I, SANDOR J. SOLTESZ, a citizen of the United States, residing in the borough of Manhattan, city, county, and 5 State of New York, have invented a new and useful Improvement in Armor Protectors for Pneumatic Tires, of which the following is a description.

This invention has reference to pneumatic 10 tires for automobiles and particularly relates to armor or protectors for the inner tube and for the shoe, case, or cover, and to a combination of elements and parts which cooperate to protect the inner tube from 15 punctures, to prevent "blow-outs", to reinforce the shoe, case, or cover, and to add strength and rigidity to the latter.

Among the objects of my invention may be noted the following: to provide a reinforce 20 for the shoe or cover of a pneumatic tire which will give strength, rigidity, firmness and durability to the shoe; to provide an armor adapted for use with and to be incorporated in a shoe or cover for pneumatic 25 tires which will reinforce the shoe and also the pneumatic tube, and will prevent "blow-outs", punctures and injuries of all nature to the inner tube; to provide an armor or protecting medium for the inner tube and for 30 the shoe or cover which is strong, durable, flexible and impenetrable; and to provide a combination of elements constituting a means for reinforcing the inner tube and the shoe, operating as a protector for both 35 the inner tube and the shoe and having all the virtues and advantages set forth in the foregoing.

With the above objects in view and others 40 which will be detailed during the course of this description, my invention consists in the parts, features, elements and combinations thereof hereinafter described and claimed.

In order that my invention may be clearly 45 understood, I have provided drawings wherein:

Figure 1 is a bottom plan view of a section of an armor or protecting medium for use in combination with automobile shoes and 50 pneumatic tires embodying my invention, the view showing a form of my invention which is efficient;

Figure 2 is a top plan view of a portion of the armor or protecting medium showing 55 the invention embodied in Figure 1;

Figure 3 is a section on the line 3—3 of Figure 1;

Figure 4 is a plan of one of the bottom armor disks showing the details thereof;

Figure 5 is a plan of one of the top armor disks showing the details thereof;

Figure 6 is a perspective view of one of the links employed to connect the top and bottom armor disks;

Figure 7 is a transverse section of shoe 65 illustrating the details of construction with my armor or protecting medium embodied therein and also illustrating the method of incorporating the armor; and

Figure 8 is a plan view of a portion of the shoe cut vertically in different places and 70 stripped so as to show the various members of the shoe and the relation and interaction of said members.

Referring to the drawings, the numeral 1 indicates one of the disks of which the armor or protecting medium is composed, this disk being shown as provided with radial projections 2, 3 and oppositely disposed circumferential notches 4, 5 and a plurality of apertures 6 disposed about the disk adjacent 75 its circumference. This disk is one of the series constituting the bottom of the armor or protecting medium.

The numeral 7 indicates a disk constituting one of a series forming the top of the armor or protecting medium. This disk is provided centrally with an aperture 8. Both the top and the bottom disks 1 and 7 are made concavo-convex or dished.

A connecting device, or link, for a series 90 of bottom disks and a top disk is shown in Figure 6, and consists of a member having four legs 9 at a right-angle to each other in the center of which is disposed a tubular sleeve 10 projecting at a right-angle to the surface of the link. The link is preferably made of a single piece of material stamped out of sheet metal, and the central tubular member is preferably struck up from the center of the link from the material constituting the central portion thereof.

In Figure 1, which shows a plurality of the disks 1 and 7 secured together to form a sheet of protecting armor, the legs of the links are shown hooked to the adjacent four disks by passing the ends of the legs 9 through adjacent apertures 6 in the disks 1 and bending them over in circular form into contact with their own bottom surface. This makes a linkage between every four 105 adjacent disks which is loose and flexible and very strong. The entire bottom of the 110

armor is composed of disks connected together by the links, as clearly shown in Figures 1 and 3. At the marginal edges of the bottom layer of the armor, narrow strips 5 of metal 11 are passed through the marginal apertures 6 of the disks 1 and bent over so as to flexibly connect the strips to the disks. The free ends of the strips 11, which are termed "anchors," are, as shown in Figure 10 7, laid in the longitudinal margins of the shoe under the beading 12 thereof. This will be more fully explained hereinafter. In constructing the armor, after the disks 1 of the bottom layer have been linked together 15 as required, the disks 7 of the top layer are secured in place upon the disks of the bottom layer by passing the tubular member 10 of the links through the central apertures 8 in the disks 7, and spreading the 20 ends of the tubes to constitute a head 13 and thus rivet the top disks to the links, so as to hold the top disks in proper relation to the bottom disks. In making this connection, the concave side of the top disks is opposed 25 to the concave side of the bottom disks, and while the top disks 7 are prevented from slipping off the tubes 10 by the heads 13 thereof, said disks can slide and rock on the tubes to accommodate themselves to movements of the armor in use. The connection 30 of the disks 7 to the tubes 10 is, therefore, loose. Thus, when the armor is completed, both surfaces will be composed of units consisting of oppositely disposed overlapping 35 disks linked together in one series and riveted in another series to the first series; and it is to be noted that the tubular rivet 10 passing through the top series of disks 7 does not hold the top series of disks rigidly 40 in contact with the lower series of disks 1. On the contrary, the disks of the top series have a slight sliding and rocking movement on the rivets and away from the circumference of the opposing disks of the bottom series. 45

As will be seen upon reference to Figure 2, the top series of disks 7 are arranged closely together so that their circumferences practically touch without overlapping each 50 other. Nevertheless, at this point, during the operation of the shoe and the flexing of the armor, there is a slight separation or gap between the adjacent edges of the said disks 7. This gap is closed so as to prevent 55 the intrusion of any pointed or foreign element by the lugs 2 and 3, which overlap the edges of adjacent disks 1 and close the gap between adjacent disks 7. The lugs 2 and 3, during the use of the shoe and the flexing 60 of the armor, have a slight sliding movement over adjacent disks 1 and relatively to cooperating disks 7, and the notches 4 and 5 of the disks 1 interact with the lugs 2 and 3 in a manner such that the walls of the 65 notches will prevent the disks 1 from shift-

ing too much laterally relatively to the links, the walls of the notches cooperating with the walls of the lugs to maintain the disks 1 in proper cooperative relation. Thus the disks 1, while having an abundance of flexibility relatively to each other and relatively to the links and the disks 7, are prevented from shifting either axially or in the direction of their circumference by the lugs 2, 3 and notches 4, 5 to eliminate any possibility 70 of strain being brought upon the legs of the links. The loose connection of the links to the disks 1 and the loose sliding connection of the links to the disks 7 provide for a maximum of flexibility in practically every 75 angular direction and enable the armor or protecting medium to flex universally so as to accommodate itself to all angular impressions made upon the circumference of the shoe and compensate for every possible distortion and angular flexure which may be imposed upon the shoe and transmitted to the armor. Therefore, while the armor or protecting medium has a maximum of flexibility, it also has a maximum of strength and 80 durability. 85

As shown in Figures 7 and 8, my armor or protecting medium is incorporated in the shoe by being practically floated in a bath of rubber gum or cement, and the said armor extends circumferentially of the shoe and from bead to bead thereof or edge to edge thereof throughout practically the entire area of the shoe. The protecting medium is secured in place along the edges 90 of the shoe by turning the anchors 11 under the outer marginal broad edge of the solidified material constituting the bead 12, the anchoring means being thus located between the body of the shoe at the bead and the material of the bead, so that when the material of the bead is secured in place within the edge of the material of the shoe it securely fastens the anchoring links in place in bent 95 condition, thus providing a strong, marginal, interlocking securing means for the armor or protecting medium, which prevents the armor from shifting, sliding or being drawn or dragged out of place. This avoids frictional heating and any possibility of 100 distortion of the armor within the shoe. 105

As shown in Figures 7 and 8, the shoe is made up of the rubber tread 14, to the inner surface of which is secured a thin piece of reinforcing canvas 15. To the reinforcing 110 canvas a layer of rubber gum 16 is applied, followed by a heavy piece of canvas 17, to which another heavy coating or layer of rubber gum 18 is applied. On the layer of 115 rubber gum 18 the armor or protecting medium is laid with the top composed of the disks 7 extending outwardly or toward the circumference of the shoe. Next a heavy layer of rubber gum 19 is applied to the 120 armor or protecting medium and then an- 125

other heavy layer of canvas 20 constituting the inner lining of the shoe. The anchoring links 11 along the edges of the armor are, as before stated, turned under the beads 12, 5 and, in the regular course of vulcanization of the constituent parts of the shoe, are caused to firmly adhere together. During the process of vulcanization, the two layers 18 and 19 of rubber applied to the opposite 10 sides of the armor become fused, so to speak, with each other and completely saturate and embed the armor therein, the armor in this sense practically floating or being suspended in the double thickness or 15 layers of rubber.

The substantial character of the armor or protecting medium constitutes a strong and durable reinforce for the shoe and also a reinforce, protector and support for the 20 pneumatic tube held within the shoe. By intervening the substantial armor or protecting medium in the body of the shoe between the tread thereof and the inner tube, "blow-outs" are prevented, undue distension of the inner tube is prevented, the inner 25 tube is rendered puncture-proof, the shoe is stabilized, rendered strong, durable and much more rigid and capable of withstanding strains, and the characteristics of the 30 armor are such that no sharp instrument such as nails, knives, glass, etc., can penetrate the shoe beyond the armor. Therefore, anything which penetrates the shoe cannot possibly reach the inner tube, and, 35 regardless of the hole made by the penetration, whether it be a hole, slit or a great gash, no "blow-out", nor puncture of the inner tube can occur, nor can leakage take 40 place, since the heavy compound layer 18, 19 of rubber constitutes practically a second inner tube through which the air cannot 45 penetrate.

Having thus described my invention, what I claim and desire to secure by Letters 5 Patent is:

1. An armor or protecting medium for automobile tires comprising a plurality of layers of concavo-convex disks, one layer of the disks being flexibly linked together and 0 another layer of disks being flexibly riveted to the disks of the first layer, said protecting medium having along its longitudinal edges 5 anchoring devices adapted to be secured to the shoe substantially as described.

2. An armor or protecting medium for automobile tires comprising a plurality of concavo-convex disks provided at opposite 10 points in their circumference with a plural-

ity of notches and a plurality of lugs, and means for flexibly linking the disks together. 15

3. An armor or protecting medium for automobile tires comprising a layer of disks arranged edge to edge, links loosely connecting the disks, a second layer of disks arranged edge to edge and overlapping a plurality of disks of the first layer, and means carried by the links for loosely securing the second layer of disks to the first layer. 20

4. In combination with an automobile 25 shoe, a protecting medium or armor consisting of a plurality of layers of disks arranged in overlapping relation and flexibly connected together, the said armor being 30 incorporated between the layers of the constituent parts of the shoe.

5. An armor or protecting medium for automobile tires comprising a layer of flexibly connected disks, a second layer of disks 35 overlapping the first layer, and means carried by the disks of one layer for covering the gaps occurring between the disks of the other layer. 40

6. In combination with a shoe for pneumatic tires, a plurality of independent layers of textile material joined by a cementitious substance, a protecting armor consisting of a plurality of metallic members flexibly connected together and embedded in a 45 thick layer of rubber, the said armor and its rubber layer being incorporated between layers of the textile material and extended from bead-to-bead of said shoe, and the said 50 armor having along its marginal edges anchoring devices connecting it to the beads of the shoe and incorporated in the material of the shoe between the beads thereof and its body layers. 55

7. In combination with a shoe for pneumatic tires comprising a plurality of independent layers of textile material joined by a cementitious substance, a protecting armor composed of a plurality of members concavo-convex in form, said members being 60 superposed so as to give to the armor substantially a concavo-convex form, said armor being incorporated between the layers of textile material and extended from bead-to-bead of said shoe, and the said armor having along its marginal edges anchoring devices connecting it with the beads of the shoe and incorporated in the material of the shoe between the beads thereof and its body layers. 65

SANDOR J. SOLTESZ.
